UNITED STATES PATENT OFFICE.

SIGMUND BERGMANN, OF NEW YORK, N. Y., ASSIGNOR TO BERGMANN & CO., OF SAME PLACE.

SOCKET FOR ELECTRIC LAMPS.

SPECIFICATION forming part of Letters Patent No. 293,552, dated February 12, 1884.

Application filed October 9, 1882. (Model.)

To all whom it may concern:

Be it known that I, SIGMUND BERGMANN, of the city, county, and State of New York, have invented a certain new and useful Improvement in Sockets for Electric Lamps, of which the following is a specification.

My invention relates to sockets for supporting incandescent electric lamps, my object being to provide a compact, cheap, and durable socket, and one adapted to support a shade-holder in such manner that said shade-holder can be placed upon and removed from the socket without detaching the socket from the fixture which supports it, as has hitherto been necessary; and my invention consists in the novel devices and combinations of devices used in accomplishing this object, as herein-after set forth.

In the accompanying drawings, Figure 1 is a view in elevation of my improved socket supporting its shade-holder, the latter being in section and the whole being in an inverted position; Fig. 2, an elevation and partial section of the socket placed upright with the shade-holder, and also a portion of the outer casing removed; Fig. 3, a section of the lower part of the socket; Fig. 4, a plan view of the interior of the socket; Fig. 5, a section of a part of the socket, and Fig. 6 a horizontal section of the screw band or sleeve of the socket.

The socket consists of a base, A, of insulating material, preferably vulcanized fiber, to which is secured an internally and externally screw-threaded metal tube or sleeve, B. Resting on the base A, within and in contact with sleeve B, is the metal plate a, having upwardly-extending walls b b, one of which has a lug, c, holding a binding-screw, d, to which one of the circuit-wires is to be attached. The bottom of sleeve B is bent in, as shown more especially in Fig. 6, and the tube and plate a are secured by screws e e. Above the walls b b of the plate a is a piece, f, of insulating material, extending across the interior of the sleeve, 45 above the bottom of the same, and supporting a metal plate, g, which carries binding-screw d', for connecting the second circuit-wire. When the incandescent electric lamp is screwed into the sleeve B, the plate on the base of said

lamp makes contact with the plate g, and the screw-threaded ring on such base with the sleeve B, whereby circuit is completed through the lamp.

The parts just described are inclosed by a metallic case consisting, first, of a metal cap, C, provided with a screw-threaded aperture, h, which is to be screwed onto the end of a suitable fixture, and through which the circuit-wires pass to the binding-screws. In the bottom of cap C are oblong apertures, through which pass the flat-headed screws i i, which enter the base A, and which may be turned, so that their heads will cross the apertures and hold the cap C in place. A metal sleeve, D, is placed above cap C, fitting over it, a space being left between sleeves D and B. Above the screw-threaded aperture h of the metal cap C the insulating-base A has a central opening, h', through which the circuit-wires (not shown) pass to the interior of the socket within the screw-sleeve B. This sleeve B has its walls cut away on opposite sides from points near their vertical center to the base A, forming openings h'', through which tools can be introduced for drawing the circuit-wires into the space within the sleeve B, and for securing such wires to the binding-screws d d'. The circuit-connections are made while the metal sleeve D is removed from the socket, and when the circuit-connections are completed such sleeve is placed upon the socket, covering the screw-sleeve B and the openings therein and concealing the connections.

F is the shade-holder, which is provided with a plain band, G, and an inwardly-projecting rib or shoulder, k. The central ring or band, G, of the shade-holder fits over the sleeve D and surrounds the sleeve B at a little distance therefrom, and is limited in its movement on the sleeve D by the rib k. An internally-screw-threaded ring, H, of insulating material, having a flange, I, is screwed upon the end of sleeve B, between said sleeve and band G, and holds the shade-holder in position. Such ring also serves to keep the sleeve B separated from the outer portions of the socket, so as to prevent any electrical contact between them. To remove the shade-holder, it is merely necessary

to unscrew the ring H, when the shade-holder may be slipped off from the tube D.

Hitherto in all electric-light fixtures, so far as I am aware, the shade-holder has been attached at the lower part of the socket and held between the socket and fixture, so that in order to remove the shade-holder it was necessary to take off the socket from the fixture, which delay and inconvenience are obviated by my invention.

What I claim is—

1. The combination, with an incandescent electric-lamp socket, of a shade-holder removably secured directly upon said socket, whereby said shade-holder may be removed without displacing said socket, substantially as set forth.
2. The combination, with an incandescent electric-lamp socket, of a shade-holder having a central ring or band fitting over said socket, and means for removably holding said band over said socket, substantially as set forth.
3. The combination, with the inner and outer metal portions of an incandescent electric-lamp socket, of a shade-holder fitting upon said outer portion, and a removable screw-threaded flanged ring of insulating material placed between said inner and outer portions, whereby the shade-holder is held removably, substantially as set forth.
4. The combination, with the inner and outer metallic portions of an incandescent electric-lamp socket, of a removable screw-threaded insulating band or ring placed between them, substantially as set forth.

5. In an incandescent electric-lamp socket, 35 the combination, with a screw-threaded metallic sleeve, B, forming one terminal, of an insulating-piece, f, supported by a metal plate, a, above the bottom of sleeve B, the metal plate g upon piece f forming the other terminal, the binding-screws d d' within said sleeve B, and openings permitting the introduction of the circuit-wires within said sleeve B, and their proper connection with the binding-screws, substantially as set forth.

6. In an incandescent electric-lamp socket, 40 the combination, with an insulating-base perforated to permit the passage of the circuit-wires therethrough, and the socket terminals supported upon said base, of a metal cap, C, 45 secured to said base and having a central opening, h, the metal sleeve H, and securing device I, substantially as set forth.

7. In an incandescent electric-lamp socket, 50 the combination, with base A, of the metal screw-sleeve B, supported thereon and forming one terminal, the other terminal supported within said sleeve, openings h² in the sleeve B, the cap C, secured to the base A, and the sleeve D, adapted to be passed over the sleeve B, and 55 secured in position after the circuit-connections are made, substantially as set forth.

SIGMUND BERGMANN.
